UNITED STATES PATENT OFFICE.

CARL KNUT EDWARD BILD, OF NORRVIKEN, SWEDEN, ASSIGNOR TO CLAS GABRIEL TIMM, OF ENGELSBERG, SWEDEN, AND HJALMAR JOHAN DANIEL BRAUNE, OF STOCKHOLM, SWEDEN.

STEAM-BOILER.

1,208,082.

Specification of Letters Patent. Patented Dec. 12, 1916.

Application filed September 12, 1914. Serial No. 881,429.

To all whom it may concern:

Be it known that I, CARL KNUT EDWARD BILD, subject of the King of Sweden, and resident of Norrviken, in the Kingdom of Sweden, engineer, have invented certain new and useful Improvements in Steam-Boilers, Such as Locomotive-Boilers and the like, of which the following is a specification, reference being made to the accompanying drawings.

This invention relates to steam boilers such as locomotive boilers and the like, of the kind provided with a gas producer and a chamber for the combustion of the gas generated in the producer.

A steam boiler constructed according to this invention is characterized, in the first place by the fact that the producer and combustion chamber are in communication 20 with each other through an aperture or passage formed or bounded by a constricted or contracted part, which is surrounded on all sides by the water in the steam boiler, and forms part of the shell constituting the generator and the combustion chamber. By this means the shell body constituting the producer and combustion chamber, is constructed in a resistant and durable manner, while in addition the burning of the walls 30 of said aperture or passage is prevented. More than one said aperture or passage may be provided. Furthermore a steam boiler made according to this invention is characterized by among other things the fact that the combustion chamber, which is 35 situated above the producer, is cylindrical in form, whereby outside stays and bolts on same which cause expense and trouble are rendered unnecessary.

40 The invention also relates to an arrangement of the superheater tubes, when the boiler is fitted with such.

The accompanying drawings illustrate a 45 constructional example of a locomotive boiler constructed according to this invention.

Figure 1 is a vertical longitudinal section of the rear part of the steam boiler, and Fig. 2 a vertical cross section of the boiler taken through the producer and the combustion 50 chamber. Fig. 3 is a side elevation of the combustion chamber and connected superheater tubes, and Fig. 4 is a cross section of the combustion chamber.

The producer, 1, which in the present case 55 is designed for generating gas from peat or

other inferior fuel, and which gas is burnt in the combustion chamber 2 situated above the producer, is fitted with rotary, hollow grate bars 4, in which there are openings 5, through which a mixture of air and steam, (the latter being conveyed through tubes 7 into the grate bars) passes into the burning fuel resting on the grate bars.

The sheet metal shell forming the producer and combustion chamber and occupying the place of the ordinary furnace is constricted or contracted at one point, and this constriction or contraction forms a passage 14, through which the gases generated in the producer pass into the combustion chamber 70 and impinge against an arch 16 of fire proof brick built therein.

From Fig. 2 it will be seen that the combustion chamber is cylindrical in form.

In the constructional example shown, the 75 "igniting" air (forced or natural draft), with which the gas burns in the combustion chamber, is admitted into the passage 14 through ducts or twyers 15, which, like the walls bounding the passage 14, are surrounded by the water of the boiler and are therefore well protected against burning. By admitting the air in this way a thorough mingling of the same with the gas is assured. The gases of combustion pass to the 85 smoke chamber of the steam boiler through tubes 17, the rear ends of which are fixed in the front wall of the combustion chamber.

The fuel for instance peat is charged into the producer 1 through openings 8 in its 90 upper part, from which the fuel falls on to the grate. Above each opening 8 there is a vertical charging shaft 9 with a rotating charging cylinder 10 therein, driven by means of a worm wheel 13 and a worm 14. 95 The peat is automatically fed to the shaft 9 from the tender of the locomotive, by means of screw conveyers indicated in the upper part of Fig. 2.

As shown, three charging devices are provided on each side of the producer. Owing to the fact that all the charging devices are at work simultaneously, the layer of fuel on the grate is very uniform. If necessary a larger or smaller number of charging appliances may be provided.

According to the nature of the fuel used in the producer, the producer is more or less extended in front of the combustion chamber. Where the fuel is of good quality, the 110

producer need not be so long as when the fuel is of inferior quality.

The superheater tubes 18 are located laterally of the tubes 17, extending from the combustion chamber to the smoke chamber of the locomotive. These tubes also are in communication at their front ends with the smoke chamber, while their rear ends are connected to the rear part of the combustion chamber, so that the superheater tubes are traversed by part of the products of combustion, by which the steam is superheated in the smaller tubes contained in the tubes 18. In the example shown the combustion chamber 2 is provided on each side at its rear end with an extension 19 which is in communication with the combustion chamber, and from the front wall of which the corresponding superheater tubes extend to the smoke chamber. By this means the length of these tubes is increased by the distance between the front wall of the combustion chamber (if the tubes are fastened therein) and the front wall of the extension, that is to say, very considerably.

Having thus described my invention what I claim as new and desire to secure by Letters Patent is:

1. In a steam boiler of the locomotive or like type, a shell forming a gas producer and a gas combustion chamber, a constricted passage connecting said producer and

combustion chamber, the walls or said passage being in contact on all sides with the water of the boiler, and means, for introducing air for combustion, said means consisting of twyers passing through the water space and projecting into said passage, said twyers being surrounded by water for substantially the whole of their length from the point where they enter the shell of the boiler.

2. In a steam boiler of the locomotive or like type, a shell forming a gas producer and a gas combustion chamber superposed thereon, said producer extending forwardly beyond the front of the combustion chamber, a constricted passage directly connecting said producer and combustion chamber, the walls of said passage being in contact on all sides with the water of the boiler, and means, for introducing air for combustion, consisting of twyers passing through the water space and projecting into said passage, said twyers being surrounded by water for substantially the whole of their length from the point where they enter the shell of the boiler.

In witness whereof I have hereunto set my hand in presence of two witnesses.

CARL KNUT EDVARD BILD'T.
